UNITED STATES PATENT OFFICE.

WILLIAM PHILIP MILLS, OF LEICESTER, ENGLAND, ASSIGNOR TO GIMSON & CO. (LEICESTER) LIMITED, OF LEICESTER, ENGLAND, A CORPORATION OF GREAT BRITAIN.

HEEL-COMPRESSING MACHINE.

1,246,299.

Specification of Letters Patent.

Patented Nov. 13, 1917.

Application filed April 7, 1916. Serial No. 89,710.

To all whom it may concern:

Be it known that I, WILLIAM PHILIP MILLS, a subject of the King of Great Britain, citizen of Leicester, England, residing at Leicester, in the county of Leicester, England, have invented certain new and useful Improvements in Heel-Compressing Machines, of which the following is a specification.

10 This invention relates to heel compressing and analogous machines such as are employed in the manufacture of boots and shoes.

The object of the invention is to provide 15 heel compressing machines, top piece condensing machines and the like with an improved arrangement of means for automatically yielding against excessive pressure to prevent damage to the work and fracture of 20 the machine.

Excessive pressure is likely to be engendered from various causes such for instance as variation in the height of the heels or in 25 the thickness of the work operated upon, wrong adjustment of the machine in relation to the work, or displacement of the work in the mold.

In compressing heels and condensing top lifts it is highly desirable that in every case 30 the maximum pressure should be applied to the work, and in order that this pressure—which is usually very heavy—shall be utilized to obtain the desired good results without fear of damaging the machine or work, the improved relieving device the subject of 35 the present invention has been designed.

The said pressure relieving means are so constructed as to be capable of adjustment to yield at any pressure thus enabling the 40 maximum pressure to be determined according to the nature of the work or as circumstances require.

In carrying the invention into practical effect the toggle may, according to one arrangement, have operating in conjunction with it a spring the force of which is directed against the joint or center of the toggle; according to another arrangement the toggle may operate in conjunction with springs 45 the force of which is directed against the ends of the toggle, with or without a further spring acting against the center joint. The first of the arrangements just mentioned is 50 suitable for yielding under very heavy pres-

sures while the second arrangement is suitable for yielding under lighter pressures.

The pressure relieving device is situated in the head or top of the machine frame and operates by allowing the heel seat die or member to yield against the opposing pressure of the beam thus obviating excessive pressure on the work or material situated between these parts.

In further describing the invention reference will be made to the accompanying drawings wherein two concrete embodiments of the invention are illustrated by way of examples.

In the drawings referred to:—

Figure 1 is a front elevation and Fig. 2 70 is a vertical side section of the upper part or head of a heel compressing machine having the invention applied thereto.

Fig. 3 is a partly sectional front view and Fig. 4 is a partly sectional plan of the machine head fitted with an alternative form 75 of the device.

Throughout the drawings like parts are designated by the same reference characters.

In the constructional form shown in Figs. 80 1 and 2, a toggle composed of members 1 and 2, is disposed in endwise relationship to the die 3 one end of the toggle being capable of pivotal movement about a stationary fulcrum 4 and the opposite end having pivotal 85 connection with a plunger 5 slidable in the machine head 6 and constructed to carry the die 3. Disposed at right angles to the toggle is a powerful compression spring 7 which at one end takes bearing against a screwed 90 plug 8 or other screwed adjusting device in a boss 9 on the back of the head, and at the opposite end presses, through the medium of a washer 10 or other convenient intermediary device, upon the center joint 11 of the 95 toggle.

The downward movement of the die 3 is restricted by two adjusting screws 12 in the machine head 6 with which screws a shoulder 13 on the plunger 5 makes contact. Thus 100 the said screws serve to determine the normal position of the die. In its normal position, the toggle 1, 2 is as shown slightly bent from the straight position in the direction of the controlling spring 7, and in action, 105 abnormal pressure against the die 3 causes an upward movement of the plunger 5 and consequent increase in the bend or

break of the toggle which acts against the controlling spring.

The maximum pressure which this arrangement will withstand may be varied 5 either by means of the adjusting screws 12 which increase or decrease the approach of the toggle members to the straight position and so give an increased or decreased maximum pressure, or by means of the screwed 10 plug 8 (or other device) which will vary the pressure of the controlling spring 7 upon the toggle. The latter method of varying the pressure admits of a finer adjustment than the former method, but both may be 15 employed.

In the alternative arrangement shown in Figs. 3 and 4, the die or pressing member 3 is mounted in a plunger 14 slideable in the machine head 6 and a toggle composed of 20 members 15, 16 is disposed at right angles to said plunger which has pivotal connection or contactual engagement with the center joint 17.

By means of an intermediate sliding member 18, each end 19 of the toggle is influenced 25 by a powerful compression spring 20 arranged in the machine head 6, the outer ends of said springs having a bearing against a screwed plug 21 or other equivalent adjusting means in the head or frame.

In this case the toggle is normally broken or bent in the direction of the die 3 as shown in Fig. 3, and excessive pressure against the latter causes upward movement of the plunger 14 which takes effect upon the toggle tending to straighten it and so compress the controlling springs 20. The lateral thrust of the ends 19 of the toggle may be taken by cheeks 22 in the machine head against which 30 the said toggle ends bear and move, and to bend or break the toggle after straightening, a third spring 23 may be employed this acting against the center joint 17 of the toggle in a direction opposed to that in which the 35 die plunger 14 affects the joint. This third spring 23 may or may not be sufficiently powerful to materially assist the controlling springs 20 in normally sustaining the die 3 against the maximum operative pressure of 40 the machine and it is preferably arranged in conjunction with a plunger rod 24 which at one end is pivotally connected to or has contactual engagement with the center joint 17 of the toggle while the other end is slideable 45 within or through a bearing or hole 25 in the machine head 6. Suitable means (not shown) may be provided for adjusting the pressure of this supplementary spring if necessary.

50 In the last described arrangement adjusting screws in the frame such as the screws 12 (Fig. 1) may be used to determine the normal position of the pressing die, and these screws and also the beforementioned 55 screwed plugs 21 (or equivalent devices) may

be employed in the aforesaid manner to vary the resistance of the yielding device.

In both the concrete forms already described the members constituting the toggle are jointed to each other and to the contiguous parts about fulcrum pins in the known manner whereby very heavy pressure may be transmitted, and the movements of the toggle to and from the straight position may be restricted to reasonable 75 limits by co-acting shoulders 26 on the toggle members.

The pressing die or member 3 may be removably fastened in the plunger 5 or 14 by a screwed fastening device such as 27 80 (Figs. 1 and 2) or other means, and the members or parts 8, 10, 18 and 21 with which the controlling springs operate may be furnished with shanks or bosses 28 to keep said springs in position in relation 85 thereto.

The machine frame or head 6 is preferably constructed to inclose the yielding device, a removable cover plate 29 (removed in Figs. 1 and 3) being fitted to give access 90 through an opening 30 to said device when necessary. The housing for the device may, and preferably does form part of the machine frame casting 6 this having exposed bosses 9 and 31 to carry the spring adjusting plugs 8 and 21 so that these may be 95 adjusted from the outside.

The arrangement of device illustrated in Figs. 1 and 2 is suitable for yielding under very heavy pressures while the arrangement 100 illustrated in Figs. 3 and 4 is suitable for yielding under lighter pressures.

What I claim then is:—

1. In a heel compressing or analogous machine, in combination, a pressing-member, a 105 slideable plunger carrying said member, a spring controlled toggle arranged to act upon the sliding plunger whereby the pressing member is sustained so as to resist the maximum pressure but to yield under pressure in excess of the maximum, and a shoulder on the plunger adapted to determine the normal position of the pressing member.

2. In a heel compressing or analogous machine, in combination, a pressing member, a 115 slideable plunger carrying said member, a spring controlled toggle arranged to act upon the sliding plunger whereby the pressing member is sustained so as to resist the maximum pressure but to yield under pressure in excess of the maximum, a shoulder on the plunger, and adjustable devices to engage said shoulder to determine the normal position of the plunger.

3. In a heel compressing or analogous machine, in combination, a pressing member, a 125 slideable plunger carrying said member, a pair of links, a fulcrum, said links being pivotally connected together at one end, and at the opposite end pivotally connected re 130

spectively to said plunger and fulcrum, a compression spring disposed at right angles to the pair of links and arranged so that its force is directed against their connected ends, a washer intermediate of one end of said spring and the joint of the links, an adjustable threaded member against which the opposite end of said spring bears, a shoulder on the plunger, and adjustable de-

vices to engage said shoulder to determine 10 the normal position of the plunger, for the purpose described.

In testimony whereof I affix my signature in presence of two witnesses.

WILLIAM PHILIP MILLS.
